UNITED STATES PATENT OFFICE.

FRED W. RAUSKOLE, OF MEDFORD, MASSACHUSETTS.

METHOD OF FORMING MOUNTINGS FOR METAL LEAF.

1,072,992.

Specification of Letters Patent.

Patented Sept. 9, 1913.

Application filed September 3, 1912. Serial No. 718,400.

To all whom it may concern:

Be it known that I, FRED W. RAUSKOLE, a citizen of the United States of America, and a resident of Medford, in the county of 5 Middlesex and State of Massachusetts, have invented certain new and useful Improvements in Methods of Forming Mountings for Metal Leaf, of which the following is a specification.

10 This invention relates to a method of forming mountings for metal leaf, the particular object of the present invention being to provide a mounting for metal leaf and especially gold leaf which can be readily 15 handled and which may be used in the trade without the necessity of applying sizing to the leather or other material to which the leaf is to be affixed.

Heretofore in affixing gold leaf and other 20 metal leaves to leather and other materials it has been necessary to apply to the material a sizing and then overlay the sizing with a layer of metal leaf, after which the necessary characters are affixed to the material 25 by means of a heated die. This method is

objectionable for several reasons, one of the principal of which is that the sizing applied to the material often causes the material to be disfigured while the metal leaf 30 surrounding the characters and not affixed to the material by means of the die must be removed from the characters affixed to the leather or other material, and this portion of the metal leaf thus removed is scattered and lost. Where the metal leaf used 35 is gold the material thus lost is of considerable value. Moreover, in the handling of the metal leaf by this process, great care has to be exercised to keep the metal layer 40 flat and free from wrinkles. To overcome these objections the metal leaf is affixed by pressure to a suitable sheet of prepared paper, preferably paraffin paper, and then the entire surface of the metal leaf is subjected 45 to a spray of sizing which will be only affected by intense heat thereon. By this means the metal leaf is always preserved in a smooth condition over the surface of the paper and is ready for use at any time and 50 by having the sizing affixed thereto it is unnecessary to apply any sizing to the material it is desired to apply the characters to.

The invention consists of a suitable prepared paper having affixed thereto a sheet 55 of metal leaf over which is sprayed a coat-

ing of sizing, and also in the method of forming this new article of manufacture.

Of the drawings: Figure 1 represents a sheet of paper. Fig. 2 represents a sheet of metal foil. Fig. 3 represents a sheet of paper 60 having the sheet of metal foil spread thereover. Fig. 4 represents, in diagram greatly enlarged, the edges of a sheet of paper, a sheet of metal foil superimposed thereon, and a sheet of prepared paper superimposed upon said metal foil. Fig. 5 represents a sheet of the prepared paper having a sheet of metal foil affixed thereto by pressure, and showing in the upper left hand corner a coating of sizing applied thereto. 70 Fig. 6 represents an enlarged reverse view of a portion of the sheet of prepared paper having the metal foil affixed thereto, and showing its condition after a plurality of characters have been removed therefrom by 75 means of a heated die. Fig. 7 represents a portion of a book showing thereon a plurality of characters in metal leaf removed from said sheet of metal leaf and affixed thereto. 80

Similar characters designate like parts throughout the several figures of the drawings.

In the drawings, 10 represents a sheet of paper such as is ordinarily used upon which 85 to spread the sheet of metal foil 11. In the preparation of the improved mounting a sheet of metal foil 11 is spread upon one of the sheets of paper 10 and then a sheet of previously prepared paper 12 is superimposed thereon as indicated in Fig. 4 of the drawings. This sheet of paper 12 is preferably treated to a paraffin bath so that it is transparent. The three sheets are then subjected to pressure so that the sheet of 90 metal foil 11 will adhere firmly to the sheet of paraffin paper 12 and will be spread smoothly thereover. While only one series of sheets 10, 11, and 12 is shown in Fig. 4, it is obvious that in practice a plurality of these 100 series of sheets will be formed in a pile and subjected to pressure simultaneously. After the pressure has been applied the sheets of paraffin paper 12 are removed from the pile, each of these sheets having adhering 105 thereto a sheet of metal foil 11, and the sheets 10 are removed therefrom. The whole face of the metal foil 11 and that portion of the sheet of the paraffin paper 12 exposed is treated to a spray of suitable siz- 110

ing material as shown at 13 in the upper left hand corner of Fig. 5. This sizing material may be of any suitable composition that will remain impervious to moisture and is adapted to be brought into a tacky condition only when subjected to intense heat. These mountings when thus prepared are ready for the market and adapted for use when desired.

- 10 When it is desired to apply characters to leather or other material the sheet of metal leaf is laid upon the material and a heated die having the necessary characters thereon is quickly applied to the rear face of the 15 sheet of parafin paper. Owing to the transparency of this sheet 12 it is possible to work closely to the edges of the sheet of metal leaf and also to other characters which have been previously removed therefrom. 20 This application of the heated die will affect only that portion of the sizing directly opposite the characters upon the die and will cause that portion of the metal leaf to be firmly fixed to the leather or other 25 material. When this has been accomplished the sheet is removed from the material and all of the metal leaf upon the sheet of parafin paper 12 will be removed therewith except that portion thereof which has been 30 fixed to the material by the action of the heated die.

When the mounting has been used several times the appearance of the mounting will be similar to that indicated in Fig. 6 of the 35 drawings, and the appearance of the leather or other material to which the metal leaf has been applied will be similar to that shown in Fig. 7 of the drawings with no disfigurement about the characters of sizing, such as is usually found when the characters have been applied in the usual manner.

It is obvious that by means of this mounting it is unnecessary to cut up the sheets 45 of metal foil into small pieces as has been customary, and by this means much waste of material is obviated. Moreover, all the metal leaf not used remains affixed to the sheet of parafin paper, and when the entire surface of the mounting has been utilized these sheets are accumulated and burned and the metal remaining thereon is thereby saved and may be returned to the manufacturer to be formed into new sheets 50 of metal foil. While any suitable sizing may be utilized, one composition thereof adapted

for this use may be mentioned, viz:—two ounces gelatin, one quart of water, two ounces glue, preferably fish glue, and one and one-half ounces of sal ammoniac. 60 These ingredients are thoroughly mixed to form a bath and preferably in order not to injure the metal leaf when fixed to the sheet of parafin paper by pressure, this composition is sprayed over the metal leaf by means 65 of any suitable spraying device, such as the ordinary air brush. When this coating of sizing has been thus sprayed over the surface of metal foil it is permitted to thoroughly dry and then the mounting is ready 70 for use.

It has been found in practice that when characters of metal leaf are applied to material by this improved method a sharper outline thereof is secured than it has been 75 possible to attain by the usual methods in general use.

It is believed that the many advantages of an article constructed in accordance with the method hereinbefore described will be 80 fully apparent without any further description.

Having thus described my invention, I claim:

1. The process of applying gold leaf consisting of supporting the gold leaf upon a sheet having a non-adhesive coating to receive said gold leaf; protecting the outer face of said gold leaf with a coating of adhesive sizing sprayed thereon, and subjecting said gold leaf and said supporting sheet to a heated tool applied with pressure to the rear face of said supporting sheet against the work to receive the gold leaf. 85

2. The process of applying gold leaf consisting of affixing the gold leaf to be applied to a waxed supporting sheet, protecting the outer face of said gold leaf from abrasion with the work to receive said gold leaf by coating said gold leaf with a fine 90 coat of adhesive sizing, and applying said gold leaf to the work by subjecting said sheet and said gold leaf to a stamping operation. 95

Signed by me at 4 Post Office Square, 105 Boston, Mass., this 29th day of August, 1912.

FRED W. RAUSKOLE.
